UNITED STATES PATENT OFFICE.

ALAN R. FERGUSSON, OF BUFFALO, NEW YORK.

TOY RAILWAY-CROSSING GATE.

Application filed February 20, 1923. Serial No. 620,173.

To all whom it may concern:

Be it known that I, ALAN R. FERGUSSON, a citizen of the United States, residing at Buffalo, in the county of Erie and State of New York, have invented certain new and useful Improvements in Toy Railway-Crossing Gates, of which the following is a specification.

This invention relates to miniature crossing gates for toy railways, an object of the invention being to provide an improved crossing gate which may be constructed at a minimum of expense, and at the same time will be strong and durable in use, and adapted to be easily manipulated by the child, thereby commanding itself to the public as an article, which may be used in connection with toy or miniature railways, of cheap, attractive and relatively indestructible character.

A further object of this invention is to provide a crossing gate for toy or miniature railways having wire formed supporting means adapted to be easily and cheaply manufactured, and providing an efficient means for supporting the crossing gate in various adjusted positions.

Other objects of this invention will appear in the following description thereof and in the appended claims, reference being had to the accompanying drawings forming a part of this specification, wherein like reference characters indicate corresponding parts in the several views and wherein Fig. 1 is a perspective view illustrating a form of my invention in position; Fig. 2 is a rear end sectional elevation; Fig. 3 is a fragmentary side view partly in section showing the crossing gate in elevated position; Fig. 4 is a fragmentary front view illustrating the crossing gate in elevated position and Fig. 5 is a detail view of the swinging miniature lantern.

Before explaining in detail the present improvement and mode of operation thereof, I desire to have it understood that the invention is not limited to the details of construction and arrangement of parts which are illustrated in the accompanying drawings, since the invention is capable of other embodiments, and that the phraseology which I employ is for the purpose of description and not of limitation.

In the preferred form of my invention

herein shown and described, it will be seen that the crossing gate comprises a relatively stationary support or stand formed from a single length of wire which is bent to provide a coiled base 9. The circular coiled wire of the base is bent inwardly at 10 to substantially the center of the coil and is then bent upwardly to form an upright or vertical post 11. The upper portion of the post 11 has the opposite sides thereof flattened at 12 thereby giving to the upper end of the post a tapered or wedge shaped configuration. The gate member for the device preferably comprises a piece of sheet metal 13 which is bent along the middle thereof into substantially U-shaped form, thereby resulting in the provision of a channel shaped member having laterally spaced sides 13^a and 13^b.

The upper tapered end 12 of the wire post 11 is inserted into the rear end of the gate member 13 and is pivoted thereto by means of a suitable pin or rivet 14 extending through the upper end of the post 11 and also through the opposite sides 13^a and 13^b of the gate member. By virtue of the pivotal connection 14 the member 13 may be swung to various positions and in order to support the forward end 15 of the gate in horizontal position as shown in Fig. 1 the same is provided with an adjustable swinging support 16. This support preferably comprises a wire of the proper length and having the upper end 17 thereof bent at right angles. The wire post or support 16 may be assembled and held in position by inserting the bent end into the channel of the gate member, so that the bent part 17 will project through an opening 18 in one side of the gate. Thereupon the sides of the member 13 may be pinched together somewhat by the operator so as to clinch the right angled portion 17 within the side walls of the channel, as shown in Fig. 4, thereby preventing the same from inadvertent displacement. The support 16 is thus swingingly connected to the gate member and when the latter is swung to its vertical position the wire 16 will be lodged or housed entirely within the channel so as to be out of sight.

The crossing gate may also be provided with a miniature or imitation swinging lantern 19. In the present instance this is

preferably stamped out of a piece of sheet metal suitably lithographed or colored so as to resemble a lantern, and comprising a curved body portion 19 having a miniature supporting handle 20. The part 20 is provided with a reduced or neck portion 21 terminating in a rounded head 22. The head 22 is bent over at right angles at the neck thereof, as shown in Fig. 5, and the lantern is hung from the gate 13 by inserting the part 20 into the channel thereof so that the bent portion 22 will project through a hole 23 in one side of the channel gate member. The head 22 may then be pinched downwardly on the outer side of the gate, and it will be seen that this construction permits the miniature lantern to swing into the channel of the gate out of sight when the gate is elevated to vertical position. Upon lowering the gate to a horizontal position as shown in Fig. 1, the lantern 19 will swing down into full view, and at the same time the wire support 16 will swing down into supporting position. The forward end 15 of the gate is preferably tapered in the direction of its length so as to resemble actual crossing gates in use at railroad crossings.

It will be further noted that the flattened tapered end 12 of the wire upright 11 not only provides an efficient and facile means for permitting the gate 13 to be directly pivoted to the wire post, but also provides locking means for holding the gate 13 in various elevated positions between the horizontal and vertical. Since the side portions 13^a and 13^b of the gate are normally spaced apart a distance substantially the same as the thickness of the post 11 at its narrowest end, when the gate 13 is elevated the lower edges of the side portions 13^a and 13^b will swing downwardly over the tapered or wedge part 12. The resiliency of the ends 24 of the gate will permit the side portions thereof to spread sufficiently to accommodate the wedge or tapered portion 12, and the resilient frictional engagement of the parts will serve to lock the gate 13 in any position to which it may be elevated.

From the foregoing it will be noted particularly that the coiled wire formed support not only furnishes a rigid and strong structure, but also may be bent up in a single operation thereby cheapening the cost of operation and manufacture. Furthermore, the wire formed upright 11 furnishes an effective means, by virtue of the flattened tapered end 12 which is readily and cheaply formed, for pivoting the gate member thereto and also for locking the same in any adjusted position.

Thus, it will be seen that the relatively stationary coiled wire support embodies at least four important advantages, namely,

cheapening the cost of manufacture, increased rigidity and stability, ready adaptability for pivotally supporting the swinging gate, and self-locking means for holding the swinging gate in any position from 70 the horizontal to the vertical.

The downwardly swinging movement of the supporting wire 16 is limited at its vertical position by means of a stop 25 which is formed by punching or projecting inwardly a portion of the metal of the gate member 13 so that when the gate is lowered to horizontal position the wire 16 will swing downwardly and engage the stop 25 upon reaching a vertical supporting position. 75 80

It is to be understood that by describing in detail herein any particular form, structure or arrangement, it is not intended to limit the invention beyond the terms of the 85 several claims or the requirements of the prior art.

Having thus explained the nature of my 90 said invention and described a way of constructing and using the same, although without attempting to set forth all of the forms in which it may be made, or all of the modes of its use, I claim:

1. A toy railway crossing gate comprising 95 a coiled wire base, a wire upright post, and a channel-shaped elongated gate member overlapping the top of said post and pivotally connected thereto for swinging movement.

2. A toy railway crossing gate comprising 100 a support formed from a single length of wire and including a coiled wire base, and a channel-shaped gate member overlapping the top of said support and pivotally connected thereto for swinging movement. 105

3. A toy railway crossing gate comprising 110 a base and an upright post, and an elongated gate member pivotally connected to said post and having both its forward and rear ends projecting beyond said post to permit the rear end to engage the post on the raising of the gate and hold it in its elevated position.

4. A toy railway crossing gate comprising 115 a base and an upright post having a tapered formation toward its upper end, and an elongated gate member pivotally connected to said post and having both its forward and rear ends projecting beyond said post to permit the rear end to frictionally engage the tapered post on the raising of the gate thereby to hold it in its elevated position.

5. A toy railway crossing gate comprising 120 a base and an upright post having a tapered formation toward the upper end of the post, and a channel-shaped crossing gate overlapping the upper end of the post and pivotally connected thereto between its ends with the forward and rear ends of the gate 125 projecting beyond said post to permit the 130

channeled rear end thereof to frictionally engage the tapered post and hold the gate in its elevated position.

6. A toy railway crossing gate comprising a wire formed base having an upright wire formed post, said post having a flattened portion tapered toward its upper end, and a channel-shaped elongated gate member pivotally connected to the post to overlap the upper end thereof and having its forward and rear ends projecting beyond the post, the channeled rear end overlapping and frictionally engaging the tapered post on the raising of the gate thereby to hold it in its elevated position.

7. A toy railway crossing gate comprising a wire formed support including a coiled wire base and an upright wire post, said post having a tapered portion, and a channel member swingingly connected thereto and adapted to engage said tapered portion for maintaining said member in adjusted position.

8. A toy railway crossing gate comprising a relatively stationary wire formed stand, an elongated gate swingingly connected adjacent to one end thereof, and a swinging wire support for the opposite end of said gate.

30 9. A toy railway crossing gate comprising a relatively stationary wire formed stand, an elongated gate swingingly connected adjacent to end thereof, a swinging wire support for the opposite end of said gate, and a miniature lantern swingingly connected to said gate.

40 10. A toy railway crossing gate comprising a U-shaped gate member, an upright post extending thereto and connected thereto, and a swinging support connected to the free end of said U-shaped member.

11. In a toy railway crossing gate the combination of an elongated gate member, a stationary wire support pivoted thereto at 45 one end, and a swinging wire support pivoted thereto at the opposite end.

50 12. In a toy railway crossing gate the combination of an elongated gate member, a stationary wire support pivoted thereto at one end, and a swinging wire support pivoted thereto at the opposite end, said member having spaced side portions and said swinging wire support being housed therebetween upon elevating the gate member.

55 13. A toy railway crossing gate comprising a sheet metal gate member, a relatively stationary support pivoted at one end thereof, a swinging support pivoted at the opposite end, a miniature lantern pivoted thereto, and self-locking means for maintaining said gate in adjusted position.

60 14. A toy railway crossing gate comprising a sheet metal gate member, a relatively stationary support pivoted at one end thereof, and means for maintaining said gate in

adjusted position, said gate having pivoted thereto a swinging support and a miniature lantern, one or both adapted to be housed within a part of said gate member upon elevating the same.

70 15. A toy railway crossing gate comprising a support having a wire upright post provided with a flattened tapered portion, and a swinging gate member pivoted to said flattened portion and having its rear end projecting beyond the post and in position to lap and frictionally engage the tapered flattened post and hold said gate member in its elevated position.

75 16. A toy railway crossing gate comprising a support having an upright wire post, and an elongated swinging gate member pivotally connected to said post and having its rear end projecting beyond the post and in position to overlap and frictionally engage the post thereby to hold the gate in its elevated position.

80 17. A toy railway crossing gate comprising a support having an upright wire post, and an elongated crossing gate pivotally connected to said post and having its rear end projecting beyond the post and in position to lap the post on the elevation of the gate member, said rear end and post constructed to hold the gate in its elevated position.

85 18. A toy railway crossing gate comprising a support having an upright wire post, and an elongated crossing gate pivotally connected to said post and having its rear end projecting beyond the post and in position to lap the post on the elevation of the gate member, said rear end and post constructed to hold the gate in its elevated position, and a swinging support for the opposite end of said gate.

90 19. A toy railway crossing gate comprising a support having an upright wire post, and an elongated crossing gate pivotally connected to said post and having its rear end projecting beyond the post and in position to lap the post on the elevation of the gate member, said rear end and post constructed to hold the gate in its elevated position, a swinging support for the opposite end of said gate, and a miniature signal member connected to said gate.

95 20. In a toy railway crossing gate the combination of a supporting base having an upright wire post, a crossing gate pivotally connected at one end to said post for swinging movement, and means connected to said gate for supporting the opposite end thereof when the gate is swung into substantially horizontal position.

100 21. A toy railway crossing gate comprising a supporting base and an upright wire post, a channel-shaped elongated gate member overlapping the upper end of said post and pivotally connected thereto with the

rear end thereof projecting beyond the post and in position to overlap the post on the elevation of the gate member, said rear end and post constructed to hold the gate in its elevated position, and means pivotally connected to the gate for supporting the forward end thereof when in its lowered position.

tion and adapted to be housed within the channel-shaped gate on the elevation thereof.

Signed at city of Buffalo, county of Erie, State of New York this 16th day of February, 1923,

ALAN R. FERGUSSON.
